UNITED STATES PATENT OFFICE.

THOMAS J. JAMES, OF PHILADELPHIA, PENNSYLVANIA, ASSIGNOR TO THOMAS THOMPSON, OF PHILADELPHIA, PENNSYLVANIA.

RETAINING DEVICE FOR A RIVETING SET.

1,425,482.

Specification of Letters Patent. Patented Aug. 8, 1922.

Application filed November 10, 1919. Serial No. 336,989.

To all whom it may concern:

Be it known that I, THOMAS J. JAMES, a citizen of the United States, residing at Philadelphia, in the county of Philadelphia and State of Pennsylvania, have invented new and useful Improvements in Retaining Devices for a Riveting Set, of which the following is a specification.

The invention relates to riveting devices such as pneumatic hammers and the like and has for an object to provide a means for retaining the riveting set or die holder in operating engagement with the barrel of the riveting implement or gun, to prevent accidental discharge of the holder from the gun, should the latter be prematurely operated.

The invention comprehends among other features, a means for locking the riveting set or die holder in the barrel of the implement or gun without however preventing operation of the holder to accomplish the work of riveting. It is well known that accidents occur in places where riveting guns are used, because of the premature operation, accidental or otherwise, of the gun before the die is placed against the rivet head or work to be operated upon. In instances of this character the force produced by the mechanism of the gun, discharges the holder therefrom causing damage to the person or object which the discharged holder strikes. In order to overcome these defects I secure the die holder or riveting set so that it cannot be accidentally discharged from the barrel of the gun, with suitable means for permitting the ready removal thereof from the gun when desired.

In the further disclosure of the invention, reference is to be had to the accompanying drawings constituting a part of this specification, in which similar characters of reference denote corresponding parts in all the views, and in which—

Figure 1 is a fragmentary vertical longitudinal sectional view taken through a riveting gun showing the die holder or set lock therein.

Figure 2 is a vertical transverse sectional view taken on the line 2—2 in Figure 1, and Figure 3 is an elevation of the holder removed from the gun.

Referring more particularly to the views the numeral 10 indicates the riveting gun and 11, the barrel thereof, the latter being provided with a longitudinal groove 12 hav-

ing a spring actuated releasing button 13 on the exterior thereof, said button including a stem 14 extending inwardly to the barrel in opposed relation to the groove 12. The holder is indicated by the numeral 15 and includes a shank 16 adapted to be slid into the barrel 11, said shank having a longitudinal rib 17 fitting the groove 12 to guide the holder longitudinally in the barrel. The holder has a longitudinal cut out portion 18 in which is seated a flat spring element 19, one end of this element being embedded or suitably secured in one end of the cut out portion with the other end substantially free and adjacent the latter, said spring element is formed or provided with a locking head 20 adapted to operate in a groove 21, formed in the barrel in opposed relation to the groove 12 and thereby providing an abutting end 22.

It will be apparent that when the holder 15 is slid into the barrel, the head 20 will be pressed down into the cut out portion by reason of the resiliency of the spring element 19 until the groove 21 is reached when the spring element, because of its tendency to spring outward will cause the head 20 to be positioned in the groove, the abutting of the head against the end 22, preventing subsequent removal of the holder from the barrel, without however preventing the holder from sliding longitudinally in the barrel in order that the gun or implement may be operated in the usual manner of a pneumatic or other hammer.

Now when it is desired to remove the holder from the barrel, it is only necessary to press down upon the button 13 thereby causing a shoe 23 on the inner end of the stem 14 to bear against the head 20 and press it downwardly into the cut out portion 18, moving the head out of the plane of the abutting end 22 so that the holder can then be readily slid out of the barrel.

The device described is of a simple construction, consists of few parts and in providing the same for use with a pneumatic or other hammer, adapted particularly to riveting; the holder will be properly retained in operating position in the barrel on the gun and cannot be accidentally discharged.

Although I have shown a particular form of my invention it will be understood that I do not limit myself to the precise construction set forth in the specification and shown

in the drawings; that various slight changes may be made without departing from the spirit of the invention, and that the scope of the invention is defined in the appended 5 claim.

Having described my invention, I claim—

The combination with the barrel of a riveting hammer provided with a bore, the bore being formed with a longitudinal channel 10 on one side and with a recess diametrically opposite the channel, the walls of the recess forming shoulders, of a tool holder including a longitudinal rib engaging the channel and itself having a longitudinal channel diametrically opposite the rib, a resilient ele- 15

ment in the channel last named, an engaging device on the resilient element and proportioned for reception within the channel last named prior to movement into the recess for engaging the shoulders, the recess being proportioned to permit of limited longitudinal movement of the tool holder, and a spring mounted element countersunk in the body of the barrel and movable radially of the tool holder for forcing the engaging device into the channel to free the tool holder. 20 25

In testimony whereof I affix my signature.

THOMAS J. JAMES.
